UNITED STATES PATENT OFFICE.

EBER M. PERFECT, OF MARIANNA, ARKANSAS, ASSIGNOR OF ONE-HALF TO SMILEY M. BRADEN, OF MARIANNA, ARKANSAS.

GAME APPARATUS.

No. 888,350.

Specification of Letters Patent.

Patented May 19, 1908.

Application filed June 7, 1907. Serial No. 377,723.

To all whom it may concern:

Be it known that I, EBER M. PERFECT, a citizen of the United States, and resident of Marianna, Arkansas, have invented certain new and useful Improvements in Game Apparatus, of which the following is a specification containing a full, clear, and exact description, reference being had to the accompanying drawings, forming a part hereof.

10 My invention relates to a game apparatus, my object being to provide a game utilizing a number of cards which are arranged in a series of suites, and which cards are printed or provided with names and marks of indication corresponding to money and the usual forms of negotiable paper utilized in banking institutions and commerce for the general transaction of business.

My improved card game serves the double purpose of providing a simple, entertaining pastime, as well as familiarizing the players with different forms of negotiable paper, and the like; and being educational in the degree that mental arithmetic is constantly required during the playing of different games by means of the cards.

My invention consists in the features of novelty herein shown, described, and claimed; and in the drawings:—

30 Figure 1 is a view looking at the faces of the entire set of sixty cards made use of in my improved game; Fig. 2 is a view of the face of one of the cards of the "Note" suite; Fig. 3 is a view of the face of one of the cards 35 of the "Draft" suite; Fig. 4 is a view of the face of one of the cards of the "Currency" suite; Fig. 5 is a view of the face of one of the cards of the "Check" suite; Fig. 6 is a view 40 of the face of one of the cards of the "Silver" suite; and Fig. 7 is a view of the face of one of the cards of the "Gold" suite.

The complete deck of the game comprises sixty cards, divided into six suites, which are termed the "Note," "Draft," "Currency," "Check," "Silver," and "Gold" suites, there being fifteen cards each in the "Note" and "Currency" suites, ten cards each in the "Draft" and "Check" suites, and five cards each in the "Gold" and "Silver" suites.

50 The cards 1 of the "Note" suite are printed at each end with a value to the amount of a certain number of dollars, and adjacent this amount appears the word "Note," and upon the balance of the face of each card appears 55 the wording such as is usually employed in a

note; and, if desired, the title of the game may be printed on the face of each card. The values appearing upon the individual cards of the "Note" suite vary; and, as seen in Fig. 1, there are three cards having a value of \$100.00 each, three cards having a value of \$75.00 each, six cards having a value of \$50.00 each, and three cards having a value of \$25.00 each. These values can be varied, as desired, it only being essential that the sum of the values represented on the cards of the "Note" suite equal the total sum of the values represented on the cards of the remaining suites; namely, the "Draft," "Currency," "Check," "Silver," and "Gold" suites.

The cards 2 of the "Currency" suite are fifteen in number, and on the ends thereof are printed values represented by a certain number of dollars, and adjacent these values appears the word "Currency," and to make this suite readily discernible from the cards of the remaining suites, the printing or coloring on the "Currency" suite may be in green, or of some distinctive color. The values appearing on the "Currency" suite vary; and, as shown in Fig. 1, one card has a value of \$100.00, two cards a value of \$150.00 each, three cards a value of \$20.00 each, four cards a value of \$10.00 each, and five cards a value of \$5.00 each.

The cards 3 of the "Draft" suite are ten in number, and appearing on the face thereof, at each end, are values represented by certain amounts of money, and adjacent these values appears the word "Draft," and appearing on the remaining portion of the face of each card of this "Draft" suite is the wording such as is usually employed on bank and commercial drafts. As shown in Fig. 1, there is one card of the "Draft" suite having a value of \$100.00, one having a value of \$80.00, two having a value of \$50.00 each, three having a value of \$30.00 each, and three having a value of \$10.00 each.

The cards 4 of the "Check" suite, ten in number, have values appearing on their faces at each end, and adjacent said values appears the word "Check", and upon the central portion of the face of each card appears the wording usually employed in bank checks. As shown in Fig. 1, there is one of the cards of the "Check" suite appearing as having a valuation of \$25.00, one card having the value of \$20.00, two having the value of

\$15.00 each, three having the value of \$10.00 each, and three having the value of \$5.00 each.

The cards 5 of the "Gold" suite, of which there are five in number, have appearing on their faces at each end values indicated by sums of money, adjacent which values appears the word "Gold"; and, if desired, the printing on the face of this suite of cards may be printed in gilt, to make said cards appear distinctive relative the remaining cards of the deck. As shown in Fig. 1, one of the cards of the "Gold" suite has a valuation of \$20.00, two cards have a valuation of \$10.00 each, and two have a valuation of \$5.00 each.

The cards 6 of the "Silver" suite, which are five in number, have appearing on their faces, adjacent the ends, a valuation expressed in dollars, and adjacent said valuation appears the word "Silver," and all of the valuations of the cards of this suite are the same, to-wit, \$1.00.

One of the simpler forms of games played with my improved cards is as follows: The cards, after being thoroughly shuffled, are equally divided between the various players, and the first player now plays one of the "Note" cards onto the table, this being imperative, as the idea of the game is to take this "Note" card by playing thereon various other cards from the "Currency," "Check," "Draft," "Gold," and "Silver," suites. For instance, the first player plays a "Note" card having a valuation of \$100.00, the second player places a "Currency" card having a valuation of \$50.00 on the "Note" card, the third player places a "Draft" card having a valuation of \$30.00 on the two cards previously played, and the fourth player can take the trick by placing a card of any of the suites having a valuation of \$20.00 onto the cards previously played, thus completing the total amount of \$100.00 required to equal the amount of the "Note" card originally played. The idea of this card game is for the second, third, fourth, and subsequent players to take up the "Note" cards played by

the first players by means of cards from the "Currency," "Draft," "Check," "Gold," and "Silver," suites, which cards of each individual trick equal the amount of the "Note" card first played.

Various other games can be played with a deck of cards of my improved construction, which games afford amusement and a pleasing pastime, and require considerable skill and calculation in their execution.

I claim:—

The herein described card game apparatus, comprising a series of cards divided into a number of suites, one of which suites is marked and designated as a "Note" suite, the cards of said suite having marks representing different money values, a second suite of the cards marked and designated as a "Currency" suite, the cards of which suite are marked to represent different money values, a third suite of the cards being marked and designated as the "Draft" suite, the cards of said suite being marked to represent different money values, a fourth suite of cards being marked and designated as the "Check" suite, the cards of said suite being marked to represent different money values, a fifth suite of the cards being marked and designated as the "Gold" suite, the cards of said suite being marked to represent different money values, a sixth suite of the cards being marked and designated as a "Silver" suite, and the cards of said suite being marked to represent the same money values, and the total sum of the money values appearing on the "Currency," "Draft," "Check," "Gold," and "Silver" suites equaling the total sum of the money values appearing on the "Note" suite.

In testimony whereof, I have signed my name to this specification, in presence of two subscribing witnesses.

EBER M. PERFECT.
